(57) **CLAIM**

The ornamental design for snag-less fishing rod guide design, as shown and described.

DESCRIPTION

FIG. 1 is a perspective view of a fishing rod guide showing an embodiment of my new design;

FIG. 2 is a perspective view of a fishing rod guide on a fishing rod as background for the fishing rod guide of FIG. 1; FIGS. 3, 4, 5, and 6 are respectively side-view, top-view, bottom-view, and center-view of the fishing rod guide of FIG. 1;

FIG. 7 is a perspective view of a fishing rod guide showing an embodiment of my new design;

FIG. 8 is a perspective view of a fishing rod guide on a fishing rod as background for the fishing rod guide of FIG. 7; and, FIGS. 9, 10, 11, and 12 are respectively side-view, top-view, bottom-view, and center-view of the fishing rod guide of FIG. 7.

The dashed lines are shown for illustrative purposes only and form no part of the claimed design.
